US0D1047995S

(12) **United States Design Patent** (10) **Patent No.:** **US D1,047,995 S**
(45) **Date of Patent:** **** Oct. 22, 2024**

(54) **COMPUTER HOST**

(71) Applicant: **Acer Incorporated**, New Taipei (TW)

(72) Inventors: **Hao-Ming Chang**, New Taipei (TW);
Ker-Wei Lin, New Taipei (TW);
Yi-Heng Lee, New Taipei (TW)

(73) Assignee: **Acer Incorporated**, New Taipei (TW)

(**) Term: **15 Years**

(21) Appl. No.: **29/884,914**

(22) Filed: **Feb. 17, 2023**

(30) **Foreign Application Priority Data**

Aug. 18, 2022 (TW) 111304125

(51) **LOC (14) Cl.** **14-02**

(57) **CLAIM**

The ornamental design for a computer host as shown and described.

DESCRIPTION

FIG. 1 is a perspective view of a computer host showing our new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The dashed broken lines illustrate portions of the computer host that form no part of the claimed design. The oblique line shading shown in the drawings indicates a translucent surface.

1 Claim, 8 Drawing Sheets
